CLAIM

The ornamental design for a cookware lid handle, as shown and described.

DESCRIPTION

FIG. 1 is a perspective view of a first embodiment of the “cookware lid handle”, showing my new design;

FIG. 2 is a right side elevation view thereof; the left side elevation view being the mirror image thereof;

FIG. 3 is a top plan view thereof;

FIG. 4 is a bottom plan view thereof;

FIG. 5 is a right side plan view thereof; the left side plan view being the mirror image thereof;

FIG. 6 is a perspective view of a second embodiment of the “cookware lid handle”;

FIG. 7 is a right side elevation view thereof; the left side elevation view being the mirror image thereof;

FIG. 8 is a top plan view thereof;

FIG. 9 is a bottom plan view thereof; and,

FIG. 10 is a right side plan view thereof; the left side plan view being the mirror image thereof.

The dash-dot broken lines in FIGS. 4 and 9 represent the bounds of the claim which form no part of the claimed design.

1 Claim, 6 Drawing Sheets(56)
